(57) **CLAIM**

The ornamental design for a tray as shown and described.

DESCRIPTION

FIG. 1 is a front right perspective view of the tray in accordance with my new design;

FIG. 2 is a top plan view thereof;

FIG. 3 is a left side elevational view thereof, a right side elevational view being a mirror image of FIG. 3;

FIG. 4 is a bottom plan view thereof;

FIG. 5 is a front elevational view thereof;

FIG. 6 is a rear elevational view thereof; and,

FIG. 7 is a front right perspective view thereof shown in use on a coffee machine in broken lines.

The broken lines in the figures are directed to environment and are for illustrative purposes only; the broken lines form no part of the claimed design.
